His Attorney.

UNITED STATES PATENT OFFICE

2,269,992

ELECTRIC SWITCH

Emil Scheuermeyer, Upper Darby, Pa., assignor to
 General Electric Company, a corporation of
 New York

Application June 3, 1941, Serial No. 396,424

5 Claims. (Cl. 200—166)

The present invention relates to electric switches, and more particularly to improvements in construction of switches of the kind employable as disconnecting devices and having a switching element or blade pivoted for swinging movement to and from a closed position between relatively stationary terminal contacts.

It is common to provide some means for limiting or arresting the opening swinging movement of the switching element in such devices, and for holding the switching element in a predetermined position such as, for example, a position in which the switching element is readily engageable by a switch hook or other operating tool for removal of the element from the switch support. Fixed solid stops are used for this purpose in some forms of disconnecting switch devices. Resilient buffers, in the form of spring strips, also have been proposed for the purpose. However, in any case where a switching element of considerable size or weight is employed, there is danger of breakage of the switching element or its support if the switching element is allowed to swing freely into engagement with a solid stop. The danger of breakage of the switching element by engagement with a solid stop likewise is present in the case of a disconnecting device employing a fused switching element wherein the fuse holder includes a casing constructed of glass, porcelain, or other frangible material. The spring strip form of resilient buffer may be unsatisfactory for the reason, among others, that it is difficult to provide a spring strip of practical dimensions, which has the desired resiliency and at the same time is capable of effectively arresting and accurately positioning a large or heavy switching element.

It is one of the objects of the present invention to provide, in a disconnecting switch support, a mechanism which is capable of arresting the movement of a switching element and of preventing shock of impact to the switching element or the switch support.

The invention also has for one of its more specific objects the provision of a switch support including a motion arresting means for the switching element as it swings to open position, the effectiveness of which means increases gradually as the element continues to move in the opening direction.

A further object is the provision of an improved mounting arrangement for disconnecting switch devices and the like of a simple, compact and economical construction.

Other objects and the details of that which I

consider to be novel and my invention will become apparent from the following description and the appended claims, taken in conjunction with the accompanying drawing wherein:

Fig. 1 shows, in side elevation, an exemplary form of disconnecting switch device embodying my invention; Fig. 2 is an enlarged side elevation, partially in section, showing the details of the hinge mechanism at the lower end of the device of Fig. 1 but in an opened position thereof; Fig. 3 is an exploded view showing, in perspective, the details of construction of certain of the parts of the mechanism shown in Figs. 1 and 2; and Fig. 4 is a fragmentary view of one portion of the structure illustrating a second embodiment of the invention.

As will be evident from the ensuing description, various features of the present invention are subject to modification and are suitable for employment in other forms of switch devices. Hence the embodiment shown in the drawing is for purposes of illustration only. In this embodiment the fuse support includes two insulators, 10 and 11, disposed in spaced relationship and bolted or otherwise secured at one end to a suitable base. On the outer end of the upper insulator, 10, there is supported a terminal and contact assembly including a terminal plate 13 having an upwardly projecting extension to which electric line conductors or leads may be secured by clamping devices 14. A contact 15 is rotatably supported on a pin 16 carried by a bracket 17 mounted on terminal plate 13. One or more springs 20 serve to bias contact 15 for rotation in a clockwise direction, as viewed in the drawing, and an adjustable stop screw 21 is provided on the lower end of the contact for limiting its rotation. A flexible braided conductor 22 insures good electric connection between the contact and terminal plate 13. The contact has two outwardly projecting arms 23, one of which may be seen in the drawing, for receiving therebetween and engaging the upper end of a switching element 24.

On the outer end of lower insulator 11, there is mounted a terminal plate 25 which, similarly to terminal plate 13, has an extension to which line conductors or leads may be secured by clamping devices 14. The upper part of terminal plate 25 is adapted to serve as a hinge support and has two integrally formed bracket arms 26 disposed in horizontally spaced relationship. Extending horizontally between the bracket arms 26 is a hinge bolt 27 having a hinge nut 28 cooperatively threaded thereupon. One end of

the bolt 21 is provided with a squared portion 29 for cooperatively receiving a vernier adjustment disk 31 which disk is provided around its periphery with a plurality of uniformly spaced holes 32. A plurality of holes 33, one less in number, however, than the holes 32, are uniformly spaced in a circle about the hinge bolt 27 in the outer surface of the bracket arm. The holes 33 are tapped for receiving a screw 34 extending through one of the holes 32 of the vernier disk 31 to secure the latter over the end of the hinge bolt 27 and to the bracket arm. With the hinge bolt 27 thus held fixed as regards the bracket, rotation of the hinge nut 28 will cause the latter to travel along the bolt by virtue of the threaded engagement therewith. Arranged around one end of the hinge bolt 27 between the end of the nut 28 and the adjacent bracket arm, is a compression member 36 which, for example, may be a spring washer of a well known form. In a modification shown in Fig. 4, the spring washer 36' is arranged on the outer side of the bracket arm beneath the bolt head 27'. It will be readily apparent that rotation of the hinge nut 28 about the hinge bolt 27 in the clockwise direction will effect a compression of the spring washer which will gradually increase the frictional resistance of the hinge nut 28 to the turning moment.

The present invention may be embodied to advantage in switch supports for mounting of various forms of switching elements or blades, and it is not intended therefore that the invention be limited to any one particular form of switching element or blade. However, the illustrated exemplary switch support is specially suited for the mounting of switching elements embodying fuse devices having cases constructed of glass, porcelain, or other frangible material. Such a fuse device is indicated at 24 on the drawing. This fuse device may, for example, be of the form shown in United States Patent 2,188,816, issued January 30, 1940, to W. K. Rankin, and assigned to the General Electric Company, the assignee of the present invention. Fuse devices of the form shown in the Rankin patent are of considerable size and weight, particularly when designed for high current interrupting ratings. They include a fusible element, and insulating supports therefor, embedded in a body of sand or granular quartz which is contained in a tubular glass casing. Opposite ends of the glass casing are closed by metallic terminal ferrules 38 and 39, respectively, which serve for connection of the fuse unit in an electric circuit.

For mounting the switching element or fuse device 24 on the previously described switch support, appropriate fittings are applied on the upper and lower ends, respectively, of the fuse device. The fitting on the upper end of the fuse device comprises a metallic contact ring 41 clamped on the upper terminal ferrule 38 and having suitable contact surfaces for engagement by complementary surfaces on the arms 23 of the upper pivoted contact 15. Secured to the ring 41 is an operating member 42 having an eye 43 for engagement by a common form of switch hook or operating tool. The upper terminal forms no part of the present invention but is of a type well known in the art.

The lower fitting comprises a metallic ring 45 clamped on the lower terminal ferrule 39 by means of bolts 46. This ring 45 has a rearwardly extending portion defining a hook 47 for

cooperatively fitting over the hinge nut 28 and supporting the fuse device thereon. In order that the hinge nut 28 will be turned by swinging movement of the fuse device, a pair of opposite surfaces of the nut are squared as indicated at 48, the hook 47 being correspondingly slotted for cooperatively fitting over the hinge nut with a relatively close fit. The hook 47 is so shaped as regards the spacing between the back surface of the terminal plate 25 and the hinge nut 28 that the fuse device may be removed and attached to the support only in the wide opened position thereof, as indicated in Fig. 2; secured to the back surface of the hook is a leaf spring 49 which in the closed position of the switching element makes firm contact with the adjacent surface of the terminal plate.

The operation of the switch support described should be obvious. When the switching element is moved upwardly, the nut 28 will be retracted from the compression member. Since movement in the closing direction will be relatively free, particularly near the end of the closing stroke, false closing of the switch device because of binding at the pivotal end will be substantially precluded. By pulling downwardly on the operating member, as with a switch hook inserted through the eye 43, the upper contacts may be separated and the fuse device permitted to swing outwardly. Rotation of the hinge nut 28 will cause a compression of the member 36 gradually increasing the frictional resistance to the turning moment. By suitable adjustment of the hinge bolt 27 with the vernier disk 31, the compression of the spring washer can be so timed as regards the angle of rotation of the switch device 24 that the latter device may be arrested in substantially any predetermined desired opened position. It will be observed that the straight outer end 51 of the hook 47 is shaped so as to engage with the adjacent surface of the terminal plate 25 in the wide opened position of the switch device 24 providing an ultimate stop therefor.

Having described the principle of operation of my invention in what I consider to represent a preferred embodiment thereof, I desire to have it understood that the specific details shown are merely illustrative and that the invention may be carried out in other ways.

What I claim as new and desire to secure by Letters Patent of the United States is:

1. In an electric switch, a supporting structure having spaced terminals, a switching element pivoted on said structure so as to be swingable to and from closed position between said terminals, a hinge bolt secured to said supporting structure, a hinge nut rotatably arranged on said bolt supporting said switching element and movable therewith, a compression member arranged in an operative relation to said nut so as to be compressed by said nut as said switching element is moved in a predetermined direction.

2. In an electric switch, a supporting structure having spaced terminals, a switching element pivoted on said structure so as to be swingable to and from closed position between said terminals, a hinge bolt secured to said supporting structure, a hinge nut cooperatively threaded upon said bolt, means for supporting said switching element on said nut, a compression member arranged to be compressed by movement of said nut along said bolt as said switching element is moved in a predetermined direction so as to arrest the movement of said switching element in said direction.

3. In an electric switch, a supporting structure having spaced terminals, a switching element pivoted on said structure so as to be swingable to and from closed position between said terminals, a hinge bolt secured to said supporting structure, a hinge nut cooperatively threaded on said hinge bolt, said switching element having means for removably attaching said switching element to said hinge nut whereby said hinge nut is turned by swinging movement of said switching element, a compression member arranged around one end of said supporting structure and said hinge nut, said member adapted to be compressed by movement of said switching element in a predetermined direction to buff the movement thereof in said direction.

4. An electric switch, a supporting structure having spaced terminals, a switching element pivoted on said structure so as to be swingable to and from closed position between said terminals, a hinge bolt secured to said supporting structure, a hinge nut cooperatively threaded on said hinge bolt, said nut having a plane surface, a hook member on said switching element for supporting said switching element on said hinge nut, said hook member having a surface to co-

operatively engage said plane nut surface whereby said nut is turned on said hinge bolt by swinging movement of said switching element, a compression member arranged around one end of said bolt and adapted to be compressed by said nut as said switching element is moved in a predetermined direction so as to arrest the movement thereof in said direction.

5. In an electric switch, a supporting structure having spaced terminals, a switching element pivoted on said structure so as to be swingable to and from closed position between said terminals, a hinge bolt secured to said supporting structure, a hinge nut cooperatively threaded upon said hinge bolt, means for attaching said switching element to said hinge nut whereby said hinge nut will be caused to turn on said bolt by swinging movements of said switching element, a compression member arranged around one end of said bolt and adapted to be compressed by said nut as said switching element is moved in a predetermined direction, and means for adjusting said hinge bolt so as to vary the degree of compression of said compression member by a predetermined swinging movement of said switching element.

EMIL SCHEUERMAYER.
